C. C. HUTSON AND J. E. WISSLER,
PROCESS FOR PRODUCING SHADED PRINTING,
APPLICATION FILED JAN. 8, 1921.

1,402,935.

Patented Jan. 10, 1922.

UNITED STATES PATENT OFFICE.

CHARLES C. HUTSON AND JOHN E. WISSLER, OF RICHMOND, INDIANA.

PROCESS FOR PRODUCING SHADED PRINTING.

1,402,935.

Specification of Letters Patent. Patented Jan. 10, 1922.

Application filed January 8, 1921. Serial No. 435,985.

To all whom it may concern:

Be it known that we, CHARLES C. HUTSON and JOHN E. WISSLER, both citizens of the United States, residing in the city of Richmond, in the county of Wayne, State of Indiana, have invented a new and useful Process for Producing Shaded Printing, of which the following is a full, clear, and comprehensive specification and exposition, being such as will enable others to use the same with absolute exactitude.

The object of our present invention, broadly stated is to accomplish distinct improvements in the art of making engraved plates for printing, particularly for decoration or artistic purposes in connection with advertisements, whereby an advertisement may be given distinct individuality, at the same time being simple in character, easily and quickly accomplished, attractive in appearance, and which can be accomplished at a comparatively low price.

More particularly stated, our object is to provide a white on Ben Day or half tone process for making engraved plates and for producing shaded effects in the printing produced thereby.

Other special objects and particular advantages of the invention will suggest themselves in the course of the following description, and that which is new and useful will be correlated in the appended claims.

The accompanying drawings, forming a part of this specification, will assist in a more thorough understanding of the invention, in which Figure 1 is a plan view of the finished product of our invention, as it would appear printed upon paper. Figure 2 is a fragmentary view of the lower left-hand corner of the face of the matrix when it is ready for making the engraved plate therefrom. Figure 3 is a cross section, as taken on the line 3—3 of Fig. 2. Figure 4 is a face view of a portion of the engraved plate made from said matrix, the same being ready to have printing made therefrom. Figure 5 is a cross section as taken on the line 5—5 of Fig. 4. And Figures 6 and 7 show specimens of designs for Ben Day or shaded impressions which are different from that shown in the other views. Figures 2, 3, 4 and 5 are made on an enlarged scale from that of Figure 1.

In order that our invention may be more fully understood and appreciated, we will

now take up a detailed description thereof, in which we will set forth the several features as fully and as comprehensively as we may.

The successful carrying out of our invention contemplates first the preparation of a matrix, the base of which may be made in a number of ways, but the best so far attained is built up of layers of paper pasted together forming a comparatively soft cardboard body A, shown in Fig. 2.

A cross grain, milled, shaded, or otherwise designed surface is to be given to the body A by means of a die or metal plate on which is engraved the required design. The face of the die is to be contacted with the face of the body A after which the proper pressure is applied to cause the body A to form the character, in reverse, of the face of the die plate. After the die plate has been removed then we have the face of the body A provided with what is known as a Ben Day surface, as denoted by B, Figures 2 and 3.

Our invention contemplates the employment of a special ink of rather thick consistency, which is adapted to be applied with a rather soft pen or brush of a size preferred by the artist for the special work contemplated.

The designs, which are to show white in the final printing, should be drawn in pencil on the surface B, it being preferred that rather wide or heavy lines be used, probably double or spaced lines in pencil, after which said penciled lines, and the spaces between the double lines, are to be gone over or filled in with said ink by means of pen or brush, whereby the design required shows upon the Ben Day surface B on which it is superimposed.

Said ink should have the quality of expanding or rising above the surface to which it is applied, particularly when heat is applied thereto, but said ink should not spread upon the surface of the paper or be absorbed thereby. The rising of the said ink causes the lines of the drawing or design to appear in cameo, as indicated by letter C in the drawings.

After the ink and the matrix have been thoroughly dried then the matrix should be placed in a casting-box and then hot type-metal is poured directly upon and covering the surface B, and of course the lines

C of the design, thereby forming the engraved plate D having the intaglio lines E which lines E are the reverse of the lines B.

Certain portions of the plate D may be 5 cut out for the insertion of standard type or cuts, after which the plate D should be mounted when it will be ready for printing purposes.

Printing from the plate D will produce 10 the finished product upon paper, as shown in Fig. 1, wherein letter F denotes the printed shaded surface caused by the Ben Day surface B, having the white lines G which have been formed correspondingly to the 15 inked lines C and the intaglio lines E. Letters H denote the letters formed by inserted standard type into the cut out portions of the plate, and letter I denotes reproductions of the cuts.

Our process, briefly stated, consists in providing 20 a body of soft material, preferably of paper stock, preparing a plate having on its face a stock design of lines, dots or otherwise, for forming Ben Day surfaces, placing 25 the surface of said plate in contact with the surface of said soft body and applying sufficient pressure whereby the Ben Day design of the plate will be impressed on the face of the body, then outlining upon the Ben 30 Day surface of said body the design or letters to be printed in white, then filling in said outlines with a specially prepared ink which has the character of expanding slightly with heat applied thereto. After 35 the matrix above described is thoroughly dried then the next step is to place the matrix in a casting box and pour over the face of the matrix ordinary type metal in melted form whereby an exact replica of the face of the 40 matrix is formed in the face of the printing plate which is formed by type metal after it has solidified, and the said replica forms what may be termed "Reverse Stereotyping."

The final step is printing upon paper with 45 the stereotype plate to accomplish the effect as shown in Fig. 1 of the drawing.

In place of the vertical lines of the Ben Day surface it is apparent that dotted lines

J, shown in Fig. 6, or diagonal lines K shown in Fig. 7 may be employed, or any other 50 Ben Day surface may be employed as desired.

We desire that it be understood that we are not to be limited to the precise details herein set forth, but that various changes may be 55 made therein without departing from the spirit of the invention without sacrificing any of the advantages thereof.

Having now fully shown and described our invention, what we claim and desire to 60 secure by Letters Patent, is—

1. The herein described process which consists in preparing a matrix having a Ben Day surface, drawing the desired design upon the Ben Day surface with a specially 65 prepared ink, forming a stereotype plate from the face of the matrix, and then printing upon paper from the face of the said stereotyped plate.

2. The herein described process which includes providing a matrix having a Ben Day surface, drawing upon said surface a design with rather thick ink which has the quality of expanding when heat is applied thereto, forming a stereotype plate on the face of 75 the matrix whereby the inked lines of the matrix will be formed intaglio on the stereotyped plate.

3. White on Ben Day or half tone process 80 for making engraved plates for printing, which consists of providing a Ben Day matrix, superimposing thereon material forming the design to be printed in white, covering the face of the matrix with melted type metal to provide a printing plate in 85 which said material forming the design will appear intaglio in the printed plate, substantially as shown and described.

In testimony whereof we have hereunto 90 subscribed our names to this specification in the presence of two subscribing witnesses.

CHARLES C. HUTSON.
JOHN E. WISSLER.
